(57) **CLAIM**

The ornamental design for a compact disc player carrying case with belt, as shown and described.

DESCRIPTION

FIG. 1 is a front perspective view of a compact disc player carrying case with belt showing my new design with environment, the broken lines forming no part of my claimed design;

FIG. 2 is a front elevation view of the invention illustrated in FIG. 1 shown with environment, the broken lines forming no part of my claimed design;

FIG. 3 is a right elevation view of the invention illustrated in FIG. 1, shown with environment, the broken lines forming no part of my claimed design

FIG. 4 is a top plan view of the invention illustrated in FIG. 1, shown with environment, the broken lines forming no part of my claimed design

FIG. 5 is a rear elevation view of the invention illustrated in FIG. 1, shown with environment, the broken lines forming no part of my claimed design

FIG. 6 is a bottom plan view of the invention illustrated in FIG. 1, shown with environment, the broken lines forming no part of my claimed design

FIG. 7 is a right elevation view of the invention illustrated in FIG. 1, shown with environment, the broken lines forming no part of my claimed design; and,

FIG. 8 is a front perspective view of the invention shown in FIG. 1 in an open position, the broken lines representing environment and forming no part of the claimed design.
